BABY BATHING DEVICE

John R. Ward, Mill Valley, Calif.

Application December 2, 1947, Serial No. 789,147

3 Claims. (Cl. 4—185)

1

This invention relates to bathing apparatus for infants and more particularly to a safety device for supporting an infant in a tub or the like while it is being bathed.

A main object of the invention is to provide an improved baby bathing device for use in an ordinary sink or tub wherein the infant may be safely supported while it is being bathed without risk of drowning, said device being very simple in construction, easy to handle, and providing rapid drainage of soapy water from the infant whereby proper rinsing of the infant is greatly facilitated.

A further object of the invention is to provide an improved baby bathing support which is inexpensive to manufacture, adjustable to different tub or sink sizes, and which is very sturdy in construction and easy to assemble, the risk of drowning the infant being minimized by the use of the improved support, and thorough rinsing of soapy water from the infant being achieved, thereby avoiding chafing and irritation of the infant's skin, as frequently results from improper rinsing.

Further objects and advantages of the invention will become apparent from the following description and claims, and from the accompanying drawings, wherein:

Figure 1 is a longitudinal cross-sectional view taken through a conventional sink and showing an infant supported on a bathing device constructed in accordance with the present invention.

Figure 2 is a top plan view, partly broken away and partly disassembled, of the bathing device of Figure 1.

Figure 3 is an enlarged cross-sectional detail view taken on line 3—3 of Figure 2.

Figure 4 is an enlarged fragmentary side elevational view of the frame portion of the infant bathing device of Figure 1.

Figure 5 is a cross-sectional detail view taken on line 5—5 of Figure 4 and showing the manner in which the side tabs of the top perforated cover used with the frame are secured thereto.

Referring to the drawings, 11 designates the frame of the device, said frame being generally rectangular in shape and comprising four right-angled channel members, generally C-shaped in cross-section, designated at 12, 13, 14 and 15 which define the corners of the frame and are telescopically interlocked at their arms. As shown in Figure 2, the longitudinal arm of channel member 12 is telescoped into the longitudinal arm of channel member 13, the longitudinal arms of channel members 14 and 15 being telescopically interlocked in the same manner. The transverse arm of channel member 15 is telescopically re-

2

ceived in the transverse arm of member 12 and the transverse arm of member 13 is telescoped into the transverse arm of member 14 in the same fashion. This allows the frame to be adjusted to fit into any conventional tub or sink.

As shown in Figure 3, the webs of the channel members are downwardly and inwardly inclined and are releasably locked together by bolts 16 passing through registering elongated slots 17 formed in said webs, said bolts being directed inwardly of the frame and being provided with wing nuts 18 threaded thereon and bearing on washers 19.

The longitudinal webs of the channel members 15 are formed with apertures 20 shaped at their top edges to define a plurality of depending equally spaced lugs 21. Designated at 22 is a cover sheet of flexible plastic or waterproof fibre formed at its longitudinal edges with spaced tabs 23, 23 shaped and located so as to be receivable in the respective apertures 20. The sheet 22, including the tabs 23, is formed with spaced perforations 24 over its entire surface. When the tabs 23 are inserted in the apertures 20 and folded inwardly with respect to the top edges of the apertures, the lugs 21 enter the adjacent perforations 24 of the tabs 23 and secure the sheet 22 in a taut condition on the frame 11, as shown in Figure 5.

In employing the apparatus, the assembled structure is placed in a sink or tub 25, as shown in Figure 1, and the infant is placed on the taut cover sheet 22. The infant may then be bathed, the water passing through the cover apertures 24 and down the sink drain. A conventional hose and spray attachment may be provided to facilitate rinsing soapy water off the infant's body.

While a specific embodiment of a bathing apparatus for infants has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A bathing support for an infant, comprising a pair of substantially vertical frame members, means operatively connecting said frame members together for relative adjusting movement toward and away from each other to provide a support of a selected size, said frame members being formed with openings therethrough extending longitudinally thereof, each frame member having a plurality of spaced lugs extending downwardly into said openings, a flexible cover sheet

for said support, said cover sheet having opposite end portions, each end portion being formed with a longitudinally extending series of transversely extending rows of apertures, said apertures of each row being spaced to correspond to spacing of said lugs, and selected rows of apertures of said end portions of said sheet being engageable with said lugs whereby to comprise means for supporting said cover sheet between said adjusted frame members in a taut condition in accordance with the selected size of the support.

2. A bathing support for an infant, comprising a pair of substantially vertical frame members, means operatively connecting said frame members together for relative adjusting movement toward and away from each other to provide a support of a selected size, said frame members each being formed with a series of spaced downwardly directed lugs extending longitudinally thereof, a flexible cover sheet having an end portion formed with means for detachably securing the same to said lugs of one frame member, said sheet having an opposite end portion formed with a longitudinally extending series of transversely extending rows of apertures, said apertures of each row being spaced to conform to the spacing of said lugs of the opposite frame member, and a row of said apertures corresponding to the selected size of the support being engageable with said last mentioned row of lugs to support said cover sheet in a taut condition between said frame members.

3. A bathing support for an infant, comprising a pair of upstanding laterally elongated frame members of sheet material, portions of the stock

5 of said frame members being cut away to provide openings therethrough extending longitudinally thereof, stock of said frame members being formed to provide rows of laterally spaced downwardly extending lugs defining the upper margins of said openings, a flexible cover sheet for said support, said cover sheet having opposite end portions, each end portion being formed with a longitudinally extending series of transversely extending rows of apertures, said apertures of each row being spaced to conform to the spacing of said lugs, said end portions of said sheet being stretched over said frame members and tucked through said openings, and rows of said apertures corresponding to the selected spacing of said frame members detachably engaging said lugs for supporting said cover sheet between said frame members in a taut condition irrespective of the selected size of the support.
